The ornamental design for a display panel with an animated computer icon, substantially as shown and described.

DESCRIPTION

FIG. 1 is a front view of a first image of a display panel, with an animated computer icon.

FIG. 2 is a front view of a second image thereof.

FIG. 3 is a front view of a third image thereof.

FIG. 4 is a front view of a fourth image thereof; and,

FIG. 5 is a front view of a fifth image thereof.

The appearance of the display panel sequentially transitions between the images shown in FIGS. 1 through 5. The process or period in which one image transitions to another image forms no part of the claimed design.

The broken line showing of a display panel and the remainder of the graphical user interface is to illustrate environment and forms no part of the claimed design.
